UNITED STATES PATENT OFFICE.

WILLIAM T. SMITH, OF ATLANTA, GEORGIA.

BUSINESS-DIRECTORY SIGNBOARD.

Application filed September 22, 1923. Serial No. 664,209.

To all whom it may concern:

Be it known that I, WILLIAM T. SMITH, a citizen of the United States, residing at Atlanta, in the county of Fulton and State 5 of Georgia, have invented a new and useful Business-Directory Signboard, of which the following is a specification.

This invention relates to a business directory sign board adapted for displaying 10 business cards or advertisements in public places, such as halls, lobbies, or waiting rooms in auditoriums, office buildings, railway stations and the like.

The object of the invention is to provide 15 a device of this character adapted to be supported from the floor, and provided with a plurality of conveniently arranged pockets or card holders, each to be assigned to a particular individual or firm and adapted 20 to contain a considerable number of cards, which are to be freely dispensed to the public.

The advantages of the invention and the detailed construction thereof will be more 25 clearly apparent from the following detailed description taken in connection with the accompanying drawings, which illustrate the preferred form of the invention.

In the drawings:

30 Figure 1 is a perspective view of the invention.

Figure 2 is a plan view thereof.

Figure 3 is a vertical transverse section 35 through a portion of the invention.

Figure 4 is a horizontal section of the same.

The device which comprises my invention includes a pair of spaced upright posts 5, preferably of iron, and supported at their 40 lower ends by suitable base blocks 6, which are sufficiently large to prevent the board from being easily tipped over. The posts 5 are preferably of such a thickness as to leave sufficient room for two series of card holders arranged back to back. Usually a post three inches square will be preferred.

The front faces of the posts are joined by a plate 7 which is preferably of sheet metal, and may consist of one or more sections. 50 In places where both sides of the board may be observed by the public, the rear faces are joined in a similar manner. The space between the plates 7 may be closed at the top and bottom by a strip 8. The plates 7 55 may be of any size desired, and are supported high enough by the posts to be displayed

in a conspicuous position to the public. Each plate is provided with a series of pockets or holders for containing business cards or other advertising cards, as indicated at 9. In forming the pocket, the plate 7 is cut to form a pair of oppositely extending tongues 10, which are bent rearwardly, as shown in Figure 4, and their terminal portions 11 are then bent toward each other, to form bottom flaps for the pocket. A strip of metal formed into a rectangular shell forms the side walls 12 and end walls 13 of the pocket, and is supported by the bottom flaps 11. Ears 14 are struck out of each side wall 12, engaging the rear side of the plate 7 to prevent the shell from being displaced from its position. Another strip 15 extends transversely across the bottom of the pocket, and is secured by ears 16 60 which extend through and are clinched to the side walls 12. A movable bottom 17 is guided within the side and end walls 12 and 65 13, and is urged outwardly by an expansile coiled spring 18 of comparatively large 70 diameter supported on the bottom strip 15. The outer edges of the side walls 12 are turned inwardly, as at 19, to form retaining flanges for the cards 9, and the left hand 75 end 13 has its outer edge 20 turned inwardly for a similar purpose. The flanges 19 are inclined from the flange 20 outwardly as they approach the opposite end of the holder 80 and extend beyond the face of the plate 7, so that they form a guideway from which 85 the cards may be withdrawn. The right hand ends of the flanges 19 and the adjacent corners of the side walls 12 are cut 90 away, as shown at 21, so that the ends of the cards may be easily accessible to withdraw 95 the same.

The dimensions of the pockets or card holders are preferably such as to accommodate an ordinary business card, and deep enough to contain 50 or 75 cards at a time. 100 The pockets are arranged on opposite sides of the board, whenever both sides are accessible to the public. If the board is arranged to set against the wall, the rear side 105 may be blank. The cards to be arranged in the several pockets or holders are designed to constitute a classified business directory, and each card holder carries a business card of a different advertiser, who pays a specified rent for the privilege. The dimensions 110 of the card holders, as well as the size of the board, do not, however, constitute an

essential part of the invention, and various modifications may also be made in the structural details of the invention without departing from the essential principles thereof as herein claimed.

What is claimed is:

1. In a device of the character described, a pair of spaced upright posts, a plate connecting the front faces of the posts and having a plurality of pairs of opposed tongues cut therefrom, each pair of tongues leaving a rectangular opening in the plate and being bent rearwardly from their bases and having their terminal portions bent toward each other to form bottom flaps for the pockets, a rectangular shell resting on said flaps and forming side and end walls of the pocket and having ears struck out to engage the rear side of the plate for retaining the walls in position, the outer edges of the side walls being bent inwardly to form retaining flanges for the cards, a strip secured transversely across the bottom of the pocket, a movable bottom within the pocket, and a spring between said movable bottom and the transverse strip to retain the cards against said retaining flanges.

2. In a device of the character described, a plate having a plurality of card holders therein, each holder comprising a pair of opposed tongues cut from the plate leaving a rectangular opening in the plate, said tongues being bent rearwardly from their bases and having their terminal portions bent toward each other to form bottom flaps for the holder, a rectangular shell resting on said flaps and forming side and end walls of the holder and having ears struck out to engage the rear side of the plate to secure the shell in position, the outer edges of the side walls being bent inwardly to form retaining flanges for the cards, said retaining flanges being inclined outwardly to-

ward one end beyond the face of the plate, and forming guideways from which a card 45 may be withdrawn.

3. In a device of the character described, the combination of a pair of spaced upright posts, a pair of face plates joining the respective front faces and rear faces of the posts, each of said plates being provided with a plurality of rectangular pockets, each pocket having retaining flanges at three of its outer edges, and a spring held bottom in each pocket for holding cards against the 55 retaining flanges, the flanges of each pocket being in a plane which is slightly inclined outwardly to extend in front of the face of the plate, at the edge which has no flange, to provide guideways from which the cards 60 may be successively withdrawn.

4. In a device of the character described, the combination of a pair of spaced upright posts, a pair of face plates joining the respective front and rear faces of the posts, 65 plates joining the top and bottom edges of the face plates and forming with the posts and face plates a closed hollow box, each of the face plates having a plurality of pairs of opposed tongues cut therefrom, each pair of tongues leaving a rectangular opening in the plate, and having their terminal portions bent toward each other to form bottom flaps for the pockets thus formed, a rectangular shell secured within 70 each pocket and forming the side walls thereof, and a bottom resiliently supported within said side walls for supporting cards or the like, certain of the outer edges of said side walls being bent inwardly to form 75 retaining flanges for the cards.

In testimony that I claim the foregoing as my own, I have hereto affixed my signature.

WILLIAM T. SMITH.
